UNITED STATES PATENT OFFICE.

EDWARD W. TINGUE, OF NEW YORK, N. Y., ASSIGNOR TO THE TINGUE MANUFACTURING COMPANY, OF SEYMOUR, CONNECTICUT.

DESIGN FOR PILED FABRIC.

SPECIFICATION forming part of Design No. 17,451, dated July 12, 1887.

Application filed March 14, 1887. Serial No. 230,269. Term of patent 7 years.

To all whom it may concern:

Be it known that I, EDWARD W. TINGUE, of the city and State of New York, have invented and produced a new Design for Piled Fabric, 5 of which the following is a specification.

This design is for a piled fabric, such as velvets and plashes; and it consists in the design of a compound stripe running longitudinally through the center of the fabric, as represented in the accompanying photograph.

The piled fabric is of plain color at *a*, with intermediate stripe, *b*, composed of numerous narrow longitudinal stripes of contrasting col-

ors, so as to produce the artistic appearance as represented.

I claim—

The design for velvets and plashes, consisting of the design of the longitudinal central stripe composed of the numerous narrow longitudinal stripes of contrasting colors in the pile of the fabric, substantially as represented.

Signed by me this 9th day of March, 1887.

E. W. TINGUE.
